UNITED STATES PATENT OFFICE.

SAMUEL P. BURGESS AND JOHN J. BURGESS, OF ROCK ISLAND, ILLINOIS.

HOT-AIR REGISTER.

1,201,142.

Specification of Letters Patent.

Patented Oct. 10, 1916.

Application filed March 18, 1915. Serial No. 15,352.

To all whom it may concern:

Be it known that we, SAMUEL P. BURGESS and JOHN J. BURGESS, citizens of the United States, residing at Rock Island, in the county of Rock Island and State of Illinois, have invented certain new and useful Improvements in Hot-Air Registers; and we do hereby declare the following to be a full, clear, and exact description of the invention, such as will enable others skilled in the art to which it appertains to make and use the same.

This invention relates to hot-air registers for heating plants, and has for an object to provide new and improved means for connecting the external or visible portion of the register with the internal sheet metal conduit and other hidden parts.

A further object of the invention is to provide improved means whereby the outer or visible parts of the register are maintained in position by being rigidly connected with the heat-conducting pipes located within the wall.

25 A further object of the invention is to provide improved means for controlling the register, and conducting the heated air from the pipes or conduits through the grille to the exterior atmosphere.

30 With these and other objects in view the invention consists in certain features of construction, combination and arrangement of parts as will be hereinafter more fully described and claimed.

35 In the drawings:—Figure 1 is a view of the improved register in front elevation, a corner being broken away to show the internal construction. Fig. 2 is a longitudinal sectional view taken on line 2—2 of Fig. 1.

40 Fig. 3 is a transverse sectional view through each of the sides of the register as shown by lines 3—3 upon opposite sides of Fig. 1. Fig. 4 is an enlarged detail view of the manner of connecting the grille and frame to the conduits being an extension of Fig. 2 on an enlarged scale.

Like characters of reference designate corresponding parts throughout the several views.

50 The improved register which forms the subject-matter of this application is adapted to be connected to a hot-air pipe or flue shown conventionally at 10 which is located within the wall of the building being heated 55 with an offset or short air duct extending outwardly through the laths and plaster of

the wall to the radiator in question. This offset portion is indicated at 11, the outer line of the plaster being coincident with the rear side of the frame as at 12.

60 The outer edges of the offset 12 are flared outwardly to correspond to the bevel 13 of the frame 14 upon the top and parallel sides, while the bottom is also flared outwardly but on a different angle as shown more particularly at 15 in Figs. 2 and 4 to correspond with the bevel of the frame 16 along the lower edge.

65 The grille 17 is provided along its top and side edges with a bevel margin 18 corresponding to the bevel of the frame 14, and at the bottom is provided with a bevel 19 corresponding to the bevel 16 of the frame. The grille is inserted by being slipped downwardly within and against the bevel 15 of 70 the lower edge of the offset to bind such offset against the bevel 16 of the frame, and is then forced inwardly against the beveled edges of the offset and to bind such edges against the bevel 13 of the frame on three 75 sides.

75 It will thus be apparent that the offset 12 is enlarged or belled at its outer edge against the beveled edges of the frame, and that the grille 17 inserted within such belled portion serves to bind it against the beveled portions of the frame and prevent its being withdrawn therefrom. To complete the clamping of the grille against the frame and the beveled edges of the conduit, fastening 80 members as the screws 20 are inserted through or in conjunction with any convenient part of the grille to bind such grille in operative position against the edges of the conduit.

95 Upon its inner side the grille is provided with spaced ears 21, and a deflector plate 22 is hinged between such ears by a rod 22' and a roll 23 of the material of the deflector about such rod. The grille 17 is also provided with segments 24, and a spring 25 is secured to the deflector 22 as having a curved end as shown at Fig. 2 bears against the segments 24. A handle 26 is also rigidly secured to the deflector, and it is to be understood of course that the segments 24 with the springs 25 bearing against them are constructed substantially with the rod 22' as the center. By this arrangement the manipulation of the handle 26 upon the exterior of the grille serves to move the deflector upon its pivoting rod 22' to any position 100 105 110

from closed as shown in full lines to fully open as shown in dotted lines at Fig. 2, and is held by the spring in such adjusted position. The use of the spring bearing continually and bindingly against the segments serves to retain the deflector plate at any point of adjustment without the necessity of employing notches or other positive locking means.

10 We claim:—

In a warm air register and mounting means therefor, an air duct arranged to project from a flue, a frame comprising four side members and having an opening there-
15 in, the edges of the frame adjacent to the

opening being outwardly flared on three sides and inwardly flared on the remaining side, said duct projecting into the opening of the frame, and a grille having its edges beveled to form complementary members 20 with reference to the flared portions next adjacent thereto.

In testimony whereof we affix our signatures in presence of two witnesses.

SAMUEL P. BURGESS.
JOHN J. BURGESS.
